UNITED STATES PATENT OFFICE

JOSEPH A. REECE, OF TOLEDO, OHIO, ASSIGNOR TO LIBBEY-OWENS GLASS COMPANY,
OF TOLEDO, OHIO, A CORPORATION OF OHIO

DOWN-FLOW SLAB

Application filed October 9, 1924, Serial No. 742,640. Renewed June 15, 1928.

The present invention relates to sheet drawing apparatus, and has particular reference to an apparatus wherein a source of molten glass is flowed down both sides of a slab at the bottom of which the streams flowing down both sides are united and drawn from the slab in flat sheet form.

An important object of the invention is to provide a slab for use in connection with the above-mentioned process wherein the sheet will be so formed that it will not get narrower after it leaves the slab.

Another very important object of the invention is to provide a slab having means at its edges which will form suitable reinforcing means along the edges of the sheet being drawn, the said edges of the sheet being sufficient to maintain the sheet to width after it leaves the slab from which it is drawn.

A still further object of the invention is to provide a slab of this nature having means carried at its edges to form curled edges on the sheet being drawn to prevent a narrowing in of the sheet after it leaves the slab.

Other objects and advantages will become more apparent during the course of the following description.

In the drawings wherein like numerals are employed to designate like parts throughout the same.

Fig. 1 is a fragmentary longitudinal section through the sheet drawing apparatus,

Fig. 2 is a front elevation of the slab in operation,

Fig. 3 is a fragmentary elevation through a slightly different form of slab,

Fig. 4 is a similar view of a slightly modified form of slab,

Fig. 5 is an enlarged sectional detail showing the formation of the sheet edge, and

Fig. 6 is a transverse section through the sheet after it has left the slab.

In the drawings wherein for the purposes of illustration is shown the preferred embodiment of the invention, the numeral 6 designates a tank which is supplied with a source of molten glass 7. Arranged in the forward end of the tank 6 in the bottom thereof is a discharge opening 8 above which is arranged an adjustable gate 9 to control the

flow of glass through the discharge opening. Arranged below the discharge opening 8 is a slab 10 having converging sides as is clearly shown in Fig. 1. The upper end of the slab 10 is hollowed out as at 11 to form a small reservoir for the glass which has left the tank 6. The reservoir 6 overflows and two stream-like formations flow down opposite sides of the slab 10 and leave the lower end of the slab and merge forming a sheet 12.

To overcome the natural tendency of the sheet 12 to narrow after it has left the slab 10, curled lips 13 are provided through which the edge portions of the sheet pass, as clearly shown in Fig. 2 of the drawings. The edges of the sheet will thus curl as indicated in Fig. 5 by the numeral 14, forming a reinforcing edge to prevent narrowing of the sheet as above referred to. The slab is provided with the curled lips 13 at both edges thereof and on both sides so that both streams flowing down the slab will have the curled edges 14 formed thereon, thus giving a sheet similar to the sheet disclosed in Fig. 6. It is to be borne in mind that the stream-like formations flowing down the slab are sufficiently fluent or plastic to curl as indicated in Fig. 5, while at the same time they are sufficiently viscous to maintain the curled formation.

After the sheet has been suitably annealed the edge portions can be removed if desired.

The curled lip portions 13 are preferably formed integral with the slab 10, although obviously they can be formed separately and attached to the sides of the slab in a suitable manner. If it is desired burners 15 can be arranged in the drawing chamber 16 to heat the curled lips 13 to prevent freezing of the glass or to prevent a too rapid cooling of the edge portions.

The slab, as shown in Fig. 2, has a curved lower end 17, which makes the slab longer through its center than at its edges, so the sheet being drawn leaves the border portions first and the center of the slab last.

It is to be understood that the form of the invention herewith shown and described is to be taken as the preferred embodiment of the same, and that various changes in the shape, size and arrangement of parts may be resorted

to without departing from the spirit of the invention or the scope of the subjoined claims.

Claims:

1. In apparatus for forming sheet glass, a slab, means for directing a stream of glass down both sides of the slab and drawing the streams from the slab in sheet form, and means carried by the slab at the edges thereof for receiving the border portions of the streams therethrough during the descent of said streams down the slab to form an edge on the sheet to prevent narrowing thereof. 5
2. In apparatus for forming sheet glass, a slab, means for directing a stream of glass down both sides of the slab, and drawing the streams from the slab in sheet form, and means carried by the slab to form curled edges on the sheet to hold the same to width. 15
3. In apparatus for forming sheet glass, a slab, means for directing a stream of glass down both sides of the slab, and drawing the streams from the slab in sheet form, and means for forming curled edges on both sides of the sheet for holding the sheet to width. 20
4. In apparatus for forming sheet glass, a slab, means for directing a stream of glass down both sides of the slab and drawing the streams from the slab in sheet form, and means formed integral with the slab for curling the edges of the sheet to hold the same to width. 25
5. In apparatus for forming sheet glass, a slab, means for directing a stream of glass down both sides of the slab and drawing the streams from the slab in sheet form, and means carried by the slab and curved to create a channel for receiving the border portions of the streams therethrough in a manner to form an edge on the sheet to prevent narrowing thereof. 35
6. In apparatus for forming sheet glass, a slab having a curved lower end and a curled lip formed at its edges. 40
7. A slab of the character described having a curved lower end and curled lip portions formed at the edges of the slab, the lowermost portion of the lips being in a relatively higher plane than the lowermost portion of the slab. 45
8. The process of drawing sheet glass, consisting in flowing a stream of glass down both sides of a slab, forming curled edges on the streams as they flow down the slab and then drawing the streams from the slab in sheet form. 50
9. In apparatus for forming sheet glass, a slab, means for flowing a stream of glass down both sides of the slab and drawing the same therefrom in sheet form, and means for forming a curled edge on the sheet for holding the same to width. 60
10. The process of forming sheet glass consisting in flowing a plurality of streams downwardly, uniting the streams to form a sheet, and in curling the edge portions of the streams to maintain the sheet to width. 65
11. The process of forming sheet glass consisting in flowing a plurality of streams of glass downwardly, uniting the streams to form a sheet, and in curling the edge portions of the streams to maintain the sheet to width, the curled edges of one stream extending in a direction opposite to the direction of the curled edges of the other stream. 70
12. In apparatus for forming sheet glass, a substantially vertically arranged slab, means for directing a stream of glass down each side of the slab and for drawing the streams from the slab in sheet form, and means carried by the slab and arranged at the edges thereof in overlapping engagement with the border portions of the streams and before they leave the slab to maintain the sheet to width. 75
13. In apparatus for forming sheet glass, a substantially vertically arranged slab, means for directing a stream of glass down both sides of the slab and drawing the streams from the slab in sheet form, and means carried by each side of the slab at opposite edges thereof for preventing narrowing of said sheet, said last mentioned means projecting outwardly beyond the plane of the adjacent side of said slab. 80
14. In apparatus for forming sheet glass, a substantially vertically arranged slab, means for directing a stream of glass down both sides of the slab and drawing the streams from the slab in sheet form, and lips carried by each side of the slab at opposite edges thereof for preventing narrowing of said sheet, said lips projecting outwardly beyond the plane of the adjacent side of said slab. 85
15. In apparatus for forming sheet glass, a substantially vertically arranged slab, means for directing a stream of glass down both sides of the slab and drawing the streams from the slab in sheet form, and means carried by each side of the slab at opposite edges thereof for preventing narrowing of the sheet, said last mentioned means being shaped to overlap the adjacent border portions of the streams. 90
16. In apparatus for forming sheet glass, a substantially vertically arranged slab, means for directing a stream of glass down both sides of the slab and for drawing the streams from the slab in sheet form, and means carried by each side of the slab at opposite edges thereof for preventing narrowing of said sheet, said last mentioned means having portions thereof arranged in spaced relation to said slab and substantially parallel therewith for forming edges on the sheet. 95
17. In apparatus for forming sheet glass, a substantially vertically arranged slab, means for directing a stream of glass down 100

both sides of the slab and for drawing the streams from the slab in sheet form, and means carried by each side of the slab at opposite edges thereof and shaped to create a channel outwardly of the adjacent face of the slab for receiving the border portions of the streams therethrough in a manner to form edges on the sheet to prevent narrowing thereof.

18. The process of forming sheet glass, consisting in flowing a plurality of streams of molten glass downwardly in spaced relation, uniting the streams to form a sheet, and in forming reinforcing edges on the streams while moving in spaced relation, said edges extending outwardly beyond the plane of the respective stream at one side thereof only.

Signed at Toledo, in the county of Lucas, and State of Ohio, this 7th day of October, 1924.
